ATTORNEY.

UNITED STATES PATENT OFFICE.

JOHN P. DURKIN, OF PHILADELPHIA, PENNSYLVANIA, ASSIGNOR TO DURKIN CONTROLLER HANDLE COMPANY, OF PHILADELPHIA, PENNSYLVANIA, A CORPORATION OF PENNSYLVANIA.

CONTROLLER-REGULATOR.

No. 875,791.

Specification of Letters Patent.

Patented Jan. 7, 1908.

Application filed August 31, 1907. Serial No. 390,876.

To all whom it may concern:

Be it known that I, JOHN P. DURKIN, a citizen of the United States, residing at Philadelphia, in the county of Philadelphia and 5 State of Pennsylvania, have invented certain Improvements in Controller-Regulators, of which the following is a specification.

This invention relates to means for regulating the operations of electric motor controllers so that the current cannot be turned on too rapidly, and its leading object is to provide an improved construction of simple character which secures an interrupted movement in turning on the current, and a free 15 movement in turning it off.

In its preferred form, the improvements comprise stationary cam ways and movable cam ways extending transversely to the movement of revolution and engaged by a 20 ball which coacts therewith to control said movement; the stationary cam ways being formed in a flange secured to the controller casing and the movable cam ways being formed on a depending part of a cover secured to the controller shaft.

The characteristic features of the improvements will more fully appear by reference to the following description and the accompanying drawings in illustration thereof.

30 In the drawings, Figure 1 represents a sectional plan view of the invention, Fig. 2 represents a sectional elevation thereof, Fig. 3 represents a sectional perspective view of the flange with the stationary cam ways, and 35 Fig. 4 represents a sectional perspective view of the cover having a depending part with the movable cam ways.

As shown in the drawings, the part 1, which may be either a part of the controller 40 casing, or a part to be secured thereto, carries the circular flange or ring 2 containing within it the cam ways 3 and 3' forming a substantially V-shaped path for the ball 4. The cover 5, which engages the controller 45 shaft 6 and is revolved therewith by the handle 7, has the depending flange, ring or body portion 8 revoluble within the flange 2, the flange 8 having in the outer face thereof the cam ways 9 and 9' registerable with the respective ways 3 and 3' and the circular ways 10 and 10' which connect the terminal ways 9 and 9' of the oppositely disposed irregular courses.

It is to be observed that the ways 3, 9, 9',

10 and 10' are of less depth than the diameter 55 of the ball, while the way 3' increases the depth from the bottom toward the top where it is approximately equal to the diameter of the ball, so that the alternately extending projections 11 and 11' will carry the ball up 60 the way 3 or the way 3' respectively.

When the handle is revolved toward the right, the ball 4, which normally lies at the junction of the ways 3 and 3' with the way 10, is forced by the first projection 11 upwardly along the intersecting ways 3 and 9, being caught at the top thereof, at the intersection of the ways 9 and 9', by the projection 11'. The movement is thus checked until, upon relieving the pressure against the 70 handle, the ball drops along the now registering ways 3 and 9'. A further movement and relaxation of the handle effects a repetition of the operation, so that the commutator shaft 6 is given the desired step by step movement in turning on the current, through the movement of the irregular or zig-zag parts of the circular way as they are carried past the ball, the movement being without interruption when the ball lies in the plain portions 80 10 and 10' of the path. In reversing, to throw off the current, a projection 11 carries the ball up to the top of the way 3', having sufficient depth to permit the flange 8 and projections 11' forming parts thereof to 85 clear the ball, whereby the revolution of the shaft in throwing off the current is uninterrupted.

Having described my invention, I claim:

1. In a controller regulator, in combination with a revoluble shaft, means having a circular way with irregular courses extending transversely to the directions of revolution, means having intersecting ways adapted for registration with said irregular courses, and 95 a ball in said ways.

2. In a controller regulator, in combination with a revoluble shaft, a circular way having courses extending transversely to the plane thereof, means having an irregular 100 way with courses adapted for registration with said first named courses, and a ball engaged in said ways.

3. In a controller regulator, a revoluble part having a way with intersecting courses 105 extending transversely to the plane of revolution, a stationary part having a way with intersecting courses respectively adapted for

registration with courses of said first named way, and a device adapted to roll in said ways.

4. In a controller regulator, in combination with a revolute shaft, a stationary part having therein a substantially V-shaped way with a course of variable depth, a member connected to said shaft and having a depending part containing a circular way with 10 courses adapted to register with said first named courses, and a device rolling in said courses.

5. In a controller regulator, a revolute

shaft, a cover fixed to said shaft and having a depending part with a peripheral way therein, a flange overlapping said part and having a way therein, and a ball revolute in said ways.

In testimony whereof I have hereunto set my name this 24th day of August, A. D. 1907, in the presence of the subscribing witnesses.

JOHN P. DURKIN.
